Delfina Parenti, Boston, Mass.

Application March 26, 1948, Serial No. 145,393

Term of patent 14 years

(Cl. D17—14)

To all whom it may concern:

Be it known that I, Delfina Parenti, a citizen of the United States, residing at Boston, in the county of Suffolk and Commonwealth of Massachusetts, have invented a new, original, and ornamental Design for a Key Chain, of which the following is a specification, reference being had to the accompanying drawing, forming part thereof.

In the drawing:

Fig. 1 shows the front view of the ornamental key chain of this invention, and

Fig. 2 is a view of the reverse side of the miniature figure thereof.

I claim:

The ornamental design for a key chain, as shown.

DELFINA PARENTI.
